US00D842350S

(12) **United States Design Patent** (10) **Patent No.:** **US D842,350 S**
Orikawa (45) **Date of Patent:** **** Mar. 5, 2019**

(54) **SUPPORTING DEVICE FOR CLAMPING MECHANISM**

(71) Applicant: **NAGAKI SEIKI CO., LTD.**, Daito-shi, Osaka (JP)

(72) Inventor: **Tomohiro Orikawa**, Aomori (JP)

(73) Assignee: **NAGAKI SEIKI CO., LTD.**, Daito-Shi, Osaka (JP)

(**) Term: **15 Years**

(21) Appl. No.: **29/621,059**

(22) Filed: **Oct. 4, 2017**

(30) **Foreign Application Priority Data**

Apr. 7, 2017 (JP) 2017-007478

(51) **LOC (11) Cl.** **15-09**

(52) **U.S. Cl.**

USPC **D15/138**

(58) **Field of Classification Search**

CPC B23D 47/04; B23Q 1/74; B23Q 3/002; Y10T 83/758; Y10T 83/7533; Y10T 83/7697

See application file for complete search history.

(57) **CLAIM**

The ornamental design for a supporting device for clamping mechanism, as shown and described.

DESCRIPTION

FIG. 1 is a front view of the supporting device for clamping mechanism;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines in the drawings depict unclaimed environmental subject matter.

1 Claim, 4 Drawing Sheets
